UNITED STATES PATENT OFFICE.

JACOB WACHOWICZ, OF DETROIT, MICHIGAN.

SAFETY GARMENT-RACK.

1,130,044.

Specification of Letters Patent. Patented Mar. 2, 1915.

Application filed January 31, 1914. Serial No. 815,678.

To all whom it may concern:

Be it known that I, JACOB WACHOWICZ, a subject of the Emperor of Austria-Hungary, residing at Detroit, in the county of Wayne, 5 and State of Michigan, have invented certain new and useful Improvements in Safety Garment-Racks, of which the following is a specification.

This invention relates to improvements in 10 safety garment racks and more especially to that class of such devices in which wearing apparel is suspended thereon and securely locked thereto.

A primary object of this invention is the 15 provision of a garment support adapted for maintaining the clothing such as hat, coat and trousers in a well kept unmussed condition and securely locked against any possible theft of the clothing.

20 A further object of the invention is to provide a combined support to maintain a coat suspended from its shoulders and at the same time to support the trousers from the waist band thereof and to also maintain 25 a hat in a top latch device.

A still further object is the provision of a 30 garment support having a latch at the top thereof for maintaining a hat, cross arms for supporting a coat and a removable bar beneath the latter for suspension of the 35 trousers and a novel manner of securely locking all of said garment to their common support.

With these general objects in view and 35 others that will appear as the nature of the invention is better understood, the same consists in the novel combination and arrangement of parts hereinafter fully described, illustrated in the accompanying drawings 40 and pointed out in the appended claims.

In the drawings forming a part of this application and in which like numerals of reference designate corresponding parts throughout the several views:—Figure 1 is 45 a perspective view of the device having a hat, coat and trousers securely locked in supported position thereon. Fig. 2 is a perspective view of the device with the clothing removed therefrom. Figs. 3, 4 and 5 are 50 vertical detail sectional views taken upon lines 3—3, 4—4 and 5—5 respectively of Fig. 2, and Fig. 6 is a detail sectional view taken upon line 6—6 of Fig. 2.

55 Referring more in detail to the drawings and to Fig. 2 thereof, the main supporting bracket 10 is noted as adapted to be secured

to a stationary member by the hold-fast device 11 inserted through the top perforation 12 thereof. Secured to the said bracket and a forward angular depending extension 13 60 thereof is a hollow link form of cross arm 14 readily adapted for insertion in the shoulder portions of the coat 15 for suspending the same.

Beneath and at both ends of the link 14 65 there are provided lugs 16 and 17 of the form shown by the detail views Figs. 4 and 5 and which are adapted to receive and suspend therein a horizontal trousers supporting bar 18. The lug 16 is provided with a 70 socket 19 for receiving one end of the bar 18 while the lug 17 is of a general hook form having a circular opening 20 with an entrance slot 21 and adapted to receive the squared end 22 of the supporting bar through 75 said slot and upon a half turn of the bar to lock the latter in position within said hook lug.

A slot 23 extends through the bracket adjacent the top portion thereof in which is 80 adapted to vertically slide a locking hook 24 having its free end constituting a jaw 25 for coöperating with an upwardly extending jaw 26 upon the angular member 13. Alining perforations 27 are positioned 85 transversely of the bracket 10 within the plane of the slot 23 and adapted to receive a locking pin 28 therethrough at a point adjacent the locking hook 24 when lowered and thereby preventing any upward movement of said arm when the pin is in position. 90

A chain 29 is permanently secured by means of the rings 30 and 31 to the extension 13 and the pin 28.

The operation of supporting and locking 95 the clothing upon my improved bracket will be at once apparent from the above detailed description and upon a reference to Fig. 1. The trousers 32 are suspended upon the bar 18 by removing the bar from its supporting 100 lugs and threading the same through the suspenders or tape supports of the trousers and then remounting the bar in said lugs. The coat 15 is placed over the cross arm 13 in the usual manner and supported by the 105 shoulder portions thereof, while the hat 33 is engaged by its rim between the jaws 25 and 26 upon opening the jaws by moving the hook 24 upwardly after the locking pin 28 has been removed. With said locking 110 pin removed from the perforations 27 of the bracket, said pin is employed to thread

the chain 29 through one or more of the button holes 34 of the coat and through one or more of the belt straps 35 of the trousers, after which it is placed in position upon the 5 bracket 10 for locking the hat within the engaging jaws while a padlock 36 is locked through the perforation 37 of the pin and thus preventing a removal of the pin by a thief or unauthorized person and locking 10 all of the garments together and to the support.

It is evident that minor changes may be made in the details of this device as well as in the form and proportion of its different 15 elements without departing from the spirit and scope of the invention, while the adaptation of the same for holding other garments such as waists and skirts is also contemplated.

Having thus described my invention and in what manner the same is designed for use, what I claim and desire to protect by Letters Patent of the United States is:—

A combination hat and garment hanger 25 comprising a bracket formed with a vertical

slot adjacent to its outer end, an angular depending arm projecting from said bracket below said slot and formed with an upwardly-extending jaw, a complementary jaw member slidably mounted in said bracket 30 slot coöperating with said first-named jaw, said bracket being further provided with alined transverse openings communicating with the bracket slot, a bar supported transversely within the bracket openings engaging the upper end of the complementary jaw member to hold the jaws in locked position, a chain connected at one of its ends to said bar and at its other end to said depending arm, said bar adapted to project laterally 40 of the bracket at the side opposite its entrance thereto, and means associated with the projecting end of the bar to prevent its removal.

In testimony whereof I affix my signature 45 in presence of two witnesses.

JACOB WACHOWICZ.
